BOOKCASE

Spencer W. Smilie, Los Angeles, Calif.

Application June 9, 1951, Serial No. 15,475

Term of patent 14 years

(Cl. D33—2)

To all whom it may concern:

Be it known that I, Spencer W. Smilie, a citizen of the United States, residing at Los Angeles, State of California, have invented a new, original, and ornamental Design for a Bookcase, of which the following is a specification, reference being had to the accompanying drawing, forming a part hereof.

Fig. 1 is a front elevational view of a bookcase showing my new design;

Fig. 2 is an end elevational view of the bookcase;

Fig. 3 is an end elevational view showing the other end of the bookcase; and

Fig. 4 is a top plan view of the bookcase shown broken for convenience of illustration.

I claim:

The ornamental design for a bookcase, as shown.

SPENCER W. SMILIE.
